VAPOR GENERATING AND SUPERHEATING
INSTALLATION

James D. Andrew, Jr., Essex Fells, and Will H. Rowand, Madison, N. J., assignors to The Babcock & Wilcox Company, New York, N. Y., a corporation of New Jersey

Application April 16, 1949, Serial No. 87,998

8 Claims. (Cl. 122—477)

1

This invention relates to vapor generating units incorporating a high temperature superheater, and more particularly to the construction and arrangement of a steam superheater in its relation to other components of a water tube steam boiler.

In modern high capacity steam generating units operating to deliver superheat steam at high pressures, and at temperatures above 900° F., a high degree of heat is absorbed from the furnace gases by extensive steam generating surface before the gases contact the convection superheater. Nevertheless, the temperature of the furnace gases contacting the superheater will be of high value and will approach the maximum temperature which the superheater tubes are designed to withstand. The high steam generating capacity and high superheat temperatures for which such units are designed require a large amount of convection heated steam superheating surface in a high temperature heating zone, and the problems of constructing and maintaining the elements of such a superheater in their operative relationships present substantial difficulties on account of the high temperatures involved.

The main object of the invention is the provision of an improved construction and arrangement of a superheater in a vapor generating unit of the character described.

In accomplishing this object the invention involves an upright superheater gas pass having all of its walls and other boundary surfaces defined by superheater supply tubes which are pendently supported, with the saturated steam from the vapor generating tubes flowing into these wall tubes, and then to the superheater which includes a bank of tubes arranged transversely of the superheater gas pass. This arrangement eliminates various unsatisfactory provisions for expansion joints between vertically adjacent sections of the walls of such a gas pass, as in the case where suspended refractory walls have been used with the vertically adjacent sections subject to different temperatures. This arrangement also eliminates the necessity of providing a multiplicity of headers and other tubular connections for the circulation, as when water tubes connected into the vapor generating circulation system are employed to form the walls of the superheater gas pass. Furthermore, the illustrative arrangement whereby the superheater gas pass walls are all defined by superheater wall tubes eliminates the wall cooling difficulties which have been experienced, due

2

to the sluggish circulation of the wall cooling units when water tubes have been employed. Such sluggish circulation has provided inadequate wall cooling, and this resulted from the lower gas temperatures of the pertinent zone, as compared to the gas temperatures of the combustion chamber wherein the main body of the vapor generating tubes are heated. It also eliminates the use of suspended type refractory walls, which do not expand uniformly in tight condition, with the pressure parts, and are difficult if not impossible to maintain.

The various features of novelty as characterized in our invention are pointed out with particularity in the claims annexed to and forming a part of this specification, and for a better understanding of the invention, its operating advantages and the specific results attained by its use, reference should be had to the accompanying drawings and descriptive matter in which there has been illustrated and described a preferred embodiment of the invention.

In the drawings:

Fig. 1 is a vertical section through the illustrative vapor generating unit;

Fig. 2 is a fragmentary vertical section of the superheater and economizer part of the installation shown in Fig. 1, on an enlarged scale. This view is taken on the line 2—2 of Fig. 3;

Fig. 3 is a fragmentary vertical section of the Fig. 1 installation, taken on the section line 3—3 of Fig. 2; and

Figs. 4, 5, and 6 are detail views showing an illustrative structure by which the supporting beams underneath the banks of economizer tubes may be held in operative position by the upright saturated steam, or superheater, tubes, defining walls of the convection section gas passes.

The vapor generating and superheating unit shown in the drawings includes a furnace with a vertically elongated combustion chamber 10. This combustion chamber is of rectangular cross section with its walls including vapor generating tubes connected to the vapor and liquid drum 12 at their upper ends, and connected with appropriate headers such as the headers 14, 16, 18 and 20, at their lower ends. The front wall 22 includes the wall tubes 24 connecting the header 14 to the drum 12 and at the lower part of this wall there are pulverized coal burners 26—28 for firing the furnace. The lower header 18 is provided for one of the side walls and the combustion chamber wall tubes extending upwardly from that header have their upper ends connected to the upper side wall header 30. Ap-

properite tubular connections such as 31 connect the header 30 with the drum 12, and the opposite side wall is of similar construction. The lower side wall header 18 has downcomers such as 34 and 36 connecting it into the fluid circulation of the vapor generating system by connection with the water space of the drum 12, and similar downcomer and header arrangements are provided for the other furnace walls.

The vapor generating wall tubes for the rear wall 38 of the combustion chamber extend upwardly from the lower header 20. Upper parts of some of these tubes extend inwardly to define the arch 40 beneath the secondary superheater section 42 which is disposed within a lateral gas outlet 44 of the furnace. Some of the wall tubes of the rear wall 38 also extend vertically from the nose of the arch 40, as indicated at 46, across the gas flow to the secondary superheater section 42, and then extend along the furnace roof 47 to the drum 12. Others of these tubes, including some of the tubes forming the arch 40, form a screen 48 rearwardly of the superheater section 42. Above this screen these tubes also extend along the roof 47 to the drum 12.

Particles of the non-combustible residue of the pulverized fuel fired by the burners 26-28 are cooled by the radiant transmission of heat therefrom to the vapor generating tubes of the combustion chamber, and these particles separated out by gravity, in a dry condition, fall into the dry ash hopper 50 at the bottom of the furnace.

Gases leaving the combustion chamber through the outlet 44 flow horizontally into the upper end of an upright gas pass 52, as indicated by arrows 54 and 56. This gas pass is of rectangular cross section, with all of its walls defined by saturated steam tubes, or superheater supply tubes, the inlets of which are in communication with the steam space of the drum 12. For example, the rear wall 60 of the gas pass is defined by sections of upright steam tubes such as 62 and 64. Tubes having the sections 64 have upper portions 66 connected to a superheater inlet header 68 which, in turn, receives steam from the drum 12 through the tubes 70. The vertical tubular sections 62 are parts of tubes also having the forwardly inclined roof sections 72 which extend forwardly toward the roof 47 of the combustion chamber and thence upwardly and rearwardly, as indicated at 74, to the superheater inlet header 68. The roof over the tube sections 72 also involves refractory material 76, in a manner similar to the other gas pass and furnace walls of the installation.

The superheater wall tube sections 62-64 extend downwardly to the superheater header 78, and the opposite wall of the gas pass 52 is formed by a row of superheater tubes having the vertical sections 80 leading downwardly from header 68. These sections are in communication with the header 78 by the horizontal tubular sections 82 near the bottom of the gas pass 52.

The lower superheater header 78 is U-shaped with its intermediate section connecting two sides, or legs, one of which is exemplified by the side header portion 84. These header portions are directly connected to parallel upper headers 86 by a row of superheater wall tubes 88. Headers 86 receive steam from the drum 12 through tubular connections such as 90. It will be understood that the remaining side wall of the gas pass 52 as well as that of the superheater bypass 92 is formed by superheater wall tubes connected

into the superheater system in the same manner as that just described.

Steam flows from the superheater header 78 through a row of wall tube sections 94 to the inlets of the superheater tubes forming the banks of tubes 100-102 of the superheater section 104. These banks of tubes are formed by series connected U-bend tubes arranged in vertical platens and connected for series flow of steam flow through the successive banks of tubes. The steam flow then continues through the upright superheater tube sections 110 to the superheater header 112 from which groups of tubular connections 114 and 116 lead to the inlet header 120 of the secondary superheater section 42. This is shown as consisting of two horizontally spaced banks of U-tubes, series connected for steam flow from the header 120 to the outlet header 122. Steam flow from the outlet header 122 continues through a series of conduits, such as 124, to a point of use.

The superheating effect may be modified by inserting any desired number of upright return-bend tubes 111 (Fig. 1) between the header 112 and the top tube sections of the upper superheater bank 100.

The banks of tubes 100-102 of the superheater section 104 are supported from the superheater tube sections 62 and 80 of opposite gas pass walls by lugs such as 125 and 127 welded to the U-bends of successive tubes and resting upon coating lugs such as 129 and 135 welded to the tubular sections 80 and 62. Beneath the superheater 104 is an economizer section 130, including three banks of tubes 131-133 formed of series connected tube end sections in much the same manner as the banks of superheater tubes. It will be noted, however, that the economizer tubes extend at 90° to the direction of the superheater tubes.

Fig. 2 of the drawings shows the upper bank of economizer tubes 131 as supported by a beam 136 which, in turn, is supported at one end by the superheater supply tube sections 62 and at its other end by the upright superheater supply tubes 80, defining the wall between the bypass 92 and the main convection gas pass 52. There are a plurality of such beams beneath the bank of tubes 131, one of the additional beams being indicated at 138 in Fig. 3. At substantially the same level as the beams 136 and 138, there are other beams such as 140 extending beneath the bank of economizer tubes 131 in the bypass 92. The particular manner in which these beams are supported from the wall tubes for the superheater space will be described below.

The remaining banks of economizer tubes 132 and 133 in the main gas pass are similarly supported by beams such as those indicated at 141-144 in Fig. 3, the beams 138, 142, and 144, disposed underneath the tube sections of the economizer tube banks 131-133 extending through upright metallic spacer support plates such as 145-147. These plates are directly above the beams 138, 142, and 144 as indicated, and the spacer support plates are provided with openings through which the economizer tubes extend. This arrangement provides support for the pertinent parts of the economizer tubes and maintains them in operative relationship. The spacer support plates may be formed by narrow upright strips or bars such as those indicated at 148 in Fig. 4, or similar bars or strips having semi-circular notches in their vertical edges so that the strips may be inserted between the upright rows

of tubes and then turned 90° on their upright axes to bring their notched portions into engagement with the successive tubes.

The banks of economizer tubes 195—198 in the bypass 92 are supported by beams such as the beam 140, a plurality of these beams being provided for the support of each bank of economizer tubes, and the beams being supported from the superheater supply tubes 80 and the steam generating tubes such as 48 and 49 (Fig. 2). The structure by which the ends of these beams are supported from these wall tubes will be similar to that subsequently described for supporting the ends of the beams extending across the main gas pass in which the economizer tube banks 131—133 are disposed. While the steam generating tubes such as 48 and 49 are connected into the circulation of the vapor generator and are at saturated temperature, that temperature is close to the temperature of the fluid in the tubes 80 which receives saturated steam from the header 68.

As indicated in Fig. 3, the banks of economizer tubes 131—133 extend to a position about half-way across the gas pass 52. At this position, or in this vertical plane, the tubes are supported by studs such as 149 which are welded to the return bends. These studs are placed in appropriately spaced openings in upright metallic spacer support plates such as 150—152 raised upon and supported by the beams 136, 141, 143. Oppositely disposed banks 131A, 132A, and 133A, of economizer tubes are similarly supported by the spacer support plates 150—152.

Turning now to Figs. 4, 5, and 6 which disclose an illustrative structure by which the economizer beams may be supported, it is to be assumed that the beam shown in these figures is the beam 138 above referred to. Welded to the right hand end of this beam is a heavy upright plate 153, extending in the direction of a normal to the longitudinal axis of the beam, and this structure is further strengthened by the welding of lateral gusset plates such as 154 and 155 to the web of the beam and to the upright plate 153.

Welded to the opposite side of the upright plate 153 there are pairs of upright triangular plates such as 156—159. These plates extend at right angles to the heavy plate 153, as shown, and they are arranged in pairs with the spaced plates 156 and 157 disposed so as to extend between the tubes 62 and 62A. The other triangular plates 158 and 159 similarly extend between wall tubes such as 62B and 62C.

Secured to the lower ends of the plates 156—159 are horizontal plates 160 and 161 perforated to receive the lower ends of tension bolts 162 and 163. These bolts are provided with suitable securing devices at their ends to take the load at a beam end and transmit that load to the upright superheater wall tubes such as 62.

The structure by which the upper ends of the tension bolts 162 and 163 are secured in position, includes the metallic support or bearing pads 164—167 as shown in Fig. 5. These pads are welded to the tubes, with their upper ends at the same level, as shown, and it is to be understood that similar pads are secured to the diametrically opposite sides of the tubes. One of these is indicated at 168 in Fig. 4.

Resting upon the pads 164—167 is a heavy horizontal plate 169, with a similar plate 170 at the opposite sides of the tubes 62 and 62A. These plates may be welded to the tubes or secured in their operative positions by welding to a heavier bar section, or collar 171, which is disposed be-

tween the two plate sections 169 and 170 and between the adjoining tubes 62 and 62A.

The securing devices at the ends of the bolt 162 include a perforated element 172 having an upwardly convex face 173 as indicated in Fig. 4. The beam structure, and more particularly the plate component 160, rests upon this face. Below the element 172 is the nut screw-threaded upon the bolt 162. Similar elements 174 and 175 are disposed at the top of the bolt 162, but the lower face 176 of the element 174 is downwardly convex at its position of contact with the supporting element 171. This particular construction involving the convex faces minimizes stresses imposed on the tube due to any slight relative movement of the beams and their supporting tubes.

It will be understood that the supporting structure indicated at the right hand end of the plate 153 in Fig. 5, is, in detail, similar to that just described for the structure at the left hand end of the plate 153.

The fluid flow through the economizer is from the exteriorly connected header 186, through the banks of tubes 131—133, and to the upper economizer header 188. From this header the fluid flow is through exterior tubes such as 190, and in the direction of the arrow 192 to the bypass economizer inlet header 194. From this header the fluid flow is through a series 195—198 of economizer tube banks similar to those already described but disposed within the superheater bypass 92. The upper ends of these tubes are connected to a header 250 which is in communication with the drum 12 by tubular connections 253 and 255.

The front wall of the superheater gas pass 52, formed by the superheater tube sections 80, constitutes a division wall between the bypass 92 of the gas pass 52, and the separation of the bypass and the gas pass is continued below the tubular sections 80 by an upright metallic wall 252 and a similar horizontal wall section 254 to the groups of dampers 256 and 258 which control the division of the furnace gases between the bypass 92 and the gas pass 52 and thus exert controlling influence upon the heat absorption in pass 52 and thereby influence the final superheat temperature. These dampers may be automatically controlled for the purpose of maintaining a predetermined superheat temperature, by a control system which regulates the dampers in accordance with the variations in steam flow from the superheater outlets 124 and also in response to variations in the superheat temperature from a predetermined value.

The furnace gases pass from the outlets of the gas pass 52 and the bypass 92 to the heating gas inlet of an air heater 260, which operates to heat combustion air for the burners. The heated air flows through the duct work 262 from the air heater to the air enclosure 264, disposed about the burners.

The wall tubes of the combustion chamber 10 and of the gas pass 52 are pendently supported from superposed steel work at the top of the installation and the supports for headers 30, 68, 86 and the upper ends of tube sections 64 are at substantially the same level as the supports for the drum so that troublesome differential expansion is avoided and so that the closely related walls may be adequately sealed between passes and the atmosphere.

The expression "superheater supply tubes" or similar expressions, as are used in the specification or the claims, are intended as a reference

to tubes receiving steam at substantially saturated temperature.

While in accordance with the provisions of the statutes we have illustrated and described herein in the best form of our invention now known to us, those skilled in the art will understand that changes may be made in the form of the apparatus disclosed without departing from the spirit of the invention covered by our claims, and that certain features of our invention may sometimes be used to advantage without a corresponding use of other features.

What is claimed is:

1. In a high pressure vapor generating and superheating installation, a large volume combustion chamber the walls of which include top hung upright vapor generating tubes, means including similar top hung vapor generating tubes forming a lateral gas outlet for the combustion chamber, upright superheater supply wall tubes defining the walls of an upright gas pass receiving furnace gases from said combustion chamber outlet, the superheater supply tubes being pendently supported from a position corresponding to the support of the vapor generating tubes, an auxiliary fluid heater including a bank of series connected horizontal tubes disposed within said gas pass and extending transversely of the flow of gases therein, a superheater section including a bank of series connected tubes disposed within said gas pass above the tubes of said auxiliary fluid heater, and means secured to the upright superheater supply tubes for supporting the tubes of said superheater section and the tubes of the auxiliary heater from the superheater supply tubes forming opposite walls of said gas pass, all of the upright walls of the gas pass including fluid heating tubes maintaining the pertinent walls at temperatures of the same order.

2. In a high pressure vapor generating and superheating installation, a large volume combustion chamber the walls of which include top hung upright vapor generating tubes, means forming a lateral gas outlet for the upper part of the combustion chamber, upright superheater supply wall tubes defining the walls of an upright gas pass receiving furnace gases from said combustion chamber outlet the superheater supply tubes receiving vapor at saturated temperature from the vapor generating tubes, the superheater supply wall tubes being pendently supported from a position corresponding to the position from which the vapor generating tubes are supported, an auxiliary fluid heater including a bank of horizontal tubes disposed within said gas pass and extending transversely of the flow of gases therein, a superheater section including a bank of series connected tubes disposed within said gas pass above the tubes of said auxiliary fluid heater, and means secured to the upright superheater tubes for supporting the tubes of said superheater section and the tubes of the auxiliary heater from the superheater tubes forming opposite walls of said gas pass, said last named means including beams supported at their ends by the superheater supply wall tubes and disposed beneath said auxiliary heater, all of the upright walls of the gas pass including fluid heating tubes maintaining the pertinent walls at temperatures of the same order.

3. In a high pressure steam generator, a furnace, means for firing the furnace, top hung steam generating wall tubes exposed to the heat of the furnace, top hung upright superheater supply tubes defining the four walls of an up-

right main gas pass receiving gases from the furnace, the superheater supply tubes receiving steam at saturated temperature, and a convection superheater section including a bank of tubes disposed in said gas pass and supported by said superheater supply tubes, some of said steam generating tubes defining a wall of a superheater gas bypass arranged in parallel with the main gas pass, an economizer including a bank of spaced tubes disposed in the bypass and supported at one side of the bypass by said last mentioned wall and at the opposite side of the bypass by one of said four walls of the main gas pass, and means controlling the variable division of the furnace gases between the main gas pass and the bypass, all of the upright walls of the gas pass and the bypass including fluid heating tubes maintaining the pertinent walls at temperatures of the same order.

4. In a high pressure vapor and generating superheating installation, a combustion chamber the walls of which include vapor generating tubes, a vapor and liquid drum to which said tubes deliver the generated vapor, upright superheater supply tubes receiving vapor from said drum and defining the four walls of an upright main gas pass receiving gases from said combustion chamber, the vapor generating tubes and the superheater supply tubes being pendently supported from a position at the top of the installation, an economizer including a first bank of tubes arranged transversely of said gas pass and supported by said superheater wall tubes, a convection superheater section including a bank of series connected tubes extending transversely of the gas flow within said gas pass, said superheater bank of tubes being disposed forwardly of the tubes of the economizer in a gas flow sense, some of said vapor generating tubes forming a wall of a superheater gas bypass opposite a bypass wall defined by some of said superheater supply tubes, a second bank of economizer tubes within said bypass, means connecting said first and second bank of economizer tubes in series for the supply of heated liquid to said drum, means secured to some of the tubes of said last mentioned walls and another wall of the main gas pass for supporting the banks of economizer tubes and the convection superheater section, and means for variably controlling the division of furnace gases between said gas pass and the bypass, all of the upright walls of the gas pass and the bypass including fluid heating tubes maintaining the pertinent walls at temperatures of the same order.

5. In a high pressure vapor generating and superheating installation, a vertically elongated large volume combustion chamber the walls of which include top hung upright vapor generating tubes, a vapor and liquid drum to which said tubes deliver their vapor, means forming a lateral gas outlet for the combustion chamber at its upper portion, upright top hung superheater supply tubes having their inlet ends in communication with the vapor space of said drum and defining the four walls of an upright main gas pass receiving furnace gases from said combustion chamber outlet, an economizer including a bank of tubes disposed within said gas pass and extending transversely of the flow of gases therein, a convection superheater section including a bank of series connected horizontal tubes disposed within said gas pass above the tubes of said economizer, some of said superheater supply tubes and some of the vapor generating tubes defining

the upright walls of a superheater gas bypass arranged in parallel with said main gas pass, other banks of economizer tubes within the bypass, means including beams extending across said bypass and main gas pass and secured to the superheater supply tubes and the bypass vapor generating tubes for supporting the banks of economizer tubes within the main gas pass and the bypass, and means for variably controlling the division of furnace gases between the bypass and the main gas pass for superheat control, all of the upright walls of the gas pass and the bypass including fluid heating tubes maintaining the pertinent walls at temperatures of the same order.

6. In a high pressure vapor generating and superheating unit, a vertically elongated furnace, supporting steelwork at the top of the unit, upright vapor generating tubes defining the furnace walls and top supported from the steelwork, and a convection superheater including a bank of spaced tubes disposed across gas flow in an upright gas pass adjacent the furnace and receiving gases therefrom, the side walls of the gas pass being defined by rows of upright superheater supply tubes functioning as a part of means conducting vapor from the vapor generating tubes to the superheater, the upright superheater supply tubes of the gas pass walls also being top supported from the steelwork, all of the upright walls of the gas pass including fluid heating tubes maintaining the pertinent walls at temperatures of the same order.

7. In a high pressure vapor generating and superheating unit, a furnace, top hung upright vapor generating tubes defining the furnace walls, and a convection superheater including a bank of spaced tubes disposed across gas flow in an upright gas pass adjacent the furnace, at least three of the walls of the gas pass including top hung upright superheater supply tubes as a part of means conducting vapor from the vapor generating tubes to the superheater, said means including a U-shaped header disposed at a lower part of the gas pass and having the superheater supply tubes of a plurality of gas pass walls directly communicating therewith, all of the upright walls of the gas pass including fluid heating tubes maintaining the pertinent walls at temperatures of the same order.

8. In a high temperature vapor generating and

superheating unit, rows of top hung contiguously arranged vapor generating wall tubes defining the walls of a furnace of rectangular cross section, said furnace having furnace gas outlet at the upper portion thereof, means firing the furnace, a vapor and liquid drum at the upper part of the unit for the reception of the vapor and liquid mixtures from the furnace wall tubes and for the separation of vapor and liquid, wall means forming a convection gas pass of rectangular cross section extending alongside one of the furnace walls and receiving gases from said furnace gas outlet, said wall means including rows of upright contiguous superheater supply tubes along at least the side walls and the rear wall of the gas pass, said wall means also including thermal insulating material arranged exteriorly of the superheater supply wall tubes, a convection superheater arranged within the gas pass, said superheater supply wall tubes constituting parts of a tubular system conducting vapor directly from said drum to the inlet of the convection superheater, and thermal insulating material covering the walls of the furnace exteriorly of the furnace wall tubes, all of the upright walls of the gas pass including fluid heating tubes maintaining the pertinent walls at temperatures of the same order.
